UNITED STATES PATENT OFFICE

ROBERT MARTIN, OF BERLIN-CHARLOTTENBURG, GERMANY

VISIBLE-RECORD FILE

Application filed August 15, 1927, Serial No. 213,003, and in Germany August 26, 1926.

My invention relates to visible record files or card indexes of the type which includes a frame having opposed guides and a plurality of cards or sheets interchangeably supported between said guides to have an overlapping relation relative to each other.

In card indexes of this type as hitherto designed it has been the usual practice to pivotally sustain the cards so that by swinging 10 the cards upwards above any desired card, the subject matter on said card will be exposed to view. In order to enable the user to withdraw the cards singly in order to replace them by other cards or to write thereon 15 with a typewriter, means have been provided for sustaining the cards in the frame in different ways. It has for instance been suggested to secure each card to a carrier such as a wire by means of eyes or hinges formed 20 on the card, the wire being removably and preferably slidably mounted in bearing holes in the opposed guides of the frame. It has also been suggested to clamp one of the edges of the card between resiliently cooperating 25 parts of a suitable carrier. Another way of supporting the cards in the frame was by means of card holders pivotally secured to the frame and having pockets formed thereon into which the cards could be inserted so 30 as to be supported by the holder. In another card index system these pockets were replaced by tongues or other means of fixation secured to the bottom edge of the card support, such tongues or fixation means extending in parallel with the support and the 35 cards being inserted between and withdrawn from the supports in a direction parallel to them. In another system no fixation means were provided, the cards being simply inserted 40 between plain holders and being therefore liable to slip thereon and to drop out altogether.

It is an object of my invention to provide a card index in which the cards or the like 45 are prevented from slipping or dropping out from between the holders and can still be withdrawn in the simplest way by merely lifting their bottom edges and pulling them out.

50 It is a further object of my invention to

provide a card index which is simpler in construction and more reliable in use than most of the devices hitherto designed.

With these and other objects in view I am now going to describe my invention with reference to the drawings accompanying this specification and forming part thereof, which show a modified form of a card index or visible record file embodying my invention.

In the drawings—

Fig. 1 is a plan view of a frame with a number of overlapping card holders and cards or sheets mounted thereon, a plurality of such frames or holders being as a rule supported in a cabinet to be withdrawn singly 60 for use.

Fig. 2 is a cross-section.

Fig. 3 is a similar view, drawn to a larger scale, of part of the frame and card holders secured to it.

Fig. 4 is a perspective view of two card holders arranged in overlapping position.

Fig. 5 is a longitudinal cross-section of the frame and holders in Fig. 1, drawn to a larger scale and showing the holders in different 75 relative positions.

Fig. 6 is a still larger cross-section showing a modified form.

Referring first to Figs. 1-5, the individual cards 1, 1 are supported in a frame 2 which may be made of any suitable material, preferably of sheet metal, and which is lined with a wooden frame 3 in which are formed bearings for a number of superposed wires or hinge pins 4, to which are pivotally secured the card holders 5. These holders may be made of sheet metal, celluloid, compressed cardboard or some other suitable material and in the form here shown are cut out in their middle portion in order to save weight and material. Hinges 6 are formed near the upper corners of each holder, while extension portions adjoining the lower corners are bent at an angle of somewhat less than 90 degs. to the main portion of the holder, thereby forming hook-shaped rests or abutments 7 for the cards to be inserted.

Fig. 1 shows a number of such holders 5 hinged to the frame 2 between the guides 3 and the cards 1 supported thereon in over-

lapping relation, resting with their bottom edges on the hook-shaped abutments 7. Obviously the cards cannot slip out between the holders even if the frame should be held in inverted position, being prevented from dropping by the hook-shaped abutments 7 and by the pressure exerted by the overlapping holders.

On the other hand, if one of the cards is 10 to be withdrawn, its bottom edge, being entirely free and unobstructed, need merely be gripped with the fingernail and slightly lifted from the support, the overlying holders and cards being lifted along with it, until the 15 card is free of the abutments 7 of its holder. Obviously, as soon as the bottom edge of the card has been lifted above the top edges of the abutments 7, it can simply be pulled out. In order to reinsert the card between the 20 holders, all that is required is to place its top edge on the top edges of the abutments 7 forming part of the respective holder and to push the card forward so as to force its top edge beneath the overlying holder, where- 25 upon the card as a whole can be pushed in between the two holders and can be slipped over the top edges of the abutments 7 of its own holder.

Owing to this arrangement any cards, 30 folded sheets or the like can be inserted, held in position and withdrawn with the greatest ease and without losing any of the advantages afforded by the visible record system. The holders 5 can be manufactured at very low 35 cost and are strong enough to stand the inevitable wear and tear. There is no need to remove the holders, which may be permanently connected with the frame, and there is no need for employing cards or sheets prepared in any particular manner, provided 40 that they be cut to size to fit in between two holders with their bottom edge resting on the two abutments 7.

In order to enable the user to swing the 45 card holders backwards through an angle of 90 degs. or more, without the hook-shaped abutments of one holder catching in the abutments of the adjoining holder, I prefer providing inclined guide pieces 10 on each holder 50 near the abutments, the height of such guide pieces being preferably at least the same as the height of the abutments and their length and position being such as not to interfere with the adjoining holder, when the holders 55 are at rest. Fig. 5 shows how the guide pieces 10 will prevent a top holder 5 from catching in the abutments 7 of a bottom holder, the top holder, on the holders being swung back, riding on the guide pieces 10 of the bottom holder and being thus carried clear of the top edges of the abutments. The guide pieces further serve to prevent the abutments from catching in the cabinet when returning the frame into its position of rest.

60 In Fig. 6 means are shown for preventing

any undue displacement of the cards relative to their holders and more especially the catching of the top portions of the cards between the hinge pins and the frame when tilting the holders. Here segmental sheet-metal pieces 11 are secured, for instance by means of solder, to the hinge ends on each side of each holder 5, these segments 11 being disposed concentrically to the hinge axis and extending at right-angles and below the 70 holders in parallel with the walls of the frames 3. Near the inner sides of these segments curved guide rails, made of metal wire, extend concentrically between and are fixed to adjoining hinge wires 4. These guide rails, as can be guessed from the drawing, cooperate with said segments in preventing the cards from slipping out and underneath the hinge pins 4, when the holders are tilted. The top edge of each card abuts against the segments 75 on the next holder above, which slide in contact with it when the holders above are swung up, and prevent the card from slipping. When said segments have moved past the top edge of the card, the latter is still held 80 against slipping, in all positions of its own swing, by the rails 12.

The abutments 7 are shown in the drawing to be spaced from the outer bottom corners of the holders, in order to prevent their interfering with the cabinet wall in which the frames are movably located.

Obviously the abutments 7 and guide pieces 10 as well as the hinges 6 can be made separate from the body of the holder, which may be formed for instance of a cardboard or celluloid sheet, the abutments, guide pieces and hinges being made of metal and being riveted or otherwise fastened to the body.

In the example shown in the drawings the 105 holders are hinged to the frame, but obviously any other way of movably uniting them with the frame might be adopted, including a resilient connection between the parts.

I wish it to be understood that I do not desire to be limited to the exact details of construction shown and described for obvious modifications will occur to a person skilled in the art.

I claim:—

1. A card holder for card indexes comprising a body portion, an abutment near the bottom edge of and extending substantially at right angles to said body portion, and a pair of substantially semi-circular segments, one 110 on each side, near the top edge of and extending at right-angles below said portion.

2. A card index comprising a frame, card holders rockably mounted in said frame in overlapping relation and abutments near the bottom edges of said holders extending substantially at right angles thereto to form a 120 rest for the bottom edges of the cards.

3. A card index comprising a frame, card holders rockably mounted in said frame in 130

overlapping relation, means associated with said holders for preventing cards placed thereon from slipping off while allowing the cards to be lifted free of said supports without any substantial parallel displacement and 5 means for preventing said holders from hindering each other's rocking motion.

4. A card index comprising a frame, card holders rockably mounted in said frame in overlapping relation, abutments associated with said holders for preventing cards placed thereon from slipping off while allowing the cards to be lifted free of said supports without any substantial parallel displacement 10 and an inclined guide on one holder for the bottom edge of an adjoining holder.

5. A card index comprising a frame, card holders rockably mounted in said frame in overlapping relation, abutments near the bottom edges of said holders extending substantially at right-angles thereto to form a rest for the bottom edges of the cards and a curved 20 guide rail arranged on said frame near each holder to prevent slipping of the card on the same, when the holder is being tilted.

6. A card index comprising a frame, card holders rockably mounted in said frame in overlapping relation, abutments near the free edges of said holders extending substantially 25 at right angles thereto to form a rest for the bottom edges of the cards, a substantially semicircular segment formed near the top edge of each holder and at right angles thereto adapted to prevent slipping of the card 30 on the adjoining holder and a curved guide rail associated with each holder to prevent slipping of the card on the same, when the holder is being tilted.

7. A card holder for card indexes comprising a body portion and means near the bottom edge of said body portion for preventing a card placed thereon from slipping off while allowing the card to be lifted free of said body portion without any substantial parallel displacement, the middle part of said body 40 portion intermediate said means being cut out to allow the bottom edge of the card placed thereon to be gripped from below.

In testimony whereof I affix my signature.
50 ROBERT MARTIN.
